UNITED STATES PATENT OFFICE.

JOHN REICHERT, OF RACINE, WISCONSIN, ASSIGNOR OF ONE-HALF TO
LUCIUS J. ELLIOTT, OF RACINE, WISCONSIN.

DESIGN FOR A HARNESS-LOOP.

SPECIFICATION forming part of Design No. 35,515, dated December 31, 1901.

Application filed October 29, 1901. Serial No. 80,442. Term of patent 14 years.

To all whom it may concern:

Be it known that I, JOHN REICHERT, a citizen of the United States, residing at Racine, county of Racine, State of Wisconsin, have 5 invented and produced a certain new and useful Design for Harness-Loops; and I do hereby declare the following to be a full, clear, and exact description of the invention, such as will enable others skilled in the art to which it appertains to make and use the same.

This invention relates to a new and useful design for harness or tug loops.

The object of the invention is to produce an exceedingly effective and artistic design for harness-loops which will possess distinguishing features in shape or contour materially enhancing the practical utility of the article.

My invention consists in the design for harness-loops, substantially as described herein- 20 after in explaining the showing in the accompanying drawing.

The accompanying drawing shows in perspective a harness-loop embodying my invention.

My loop comprises base portions *a*, having 25 depending projections, lugs, or flanges *b*, and side uprights or walls *c* from the base portions *a* to the top cross-piece or bridge *d*.

Having thus fully described my invention, what I claim as new, and desire to secure by 30 Letters Patent of the United States, is—

The design for a harness-loop, substantially as described and shown.

In testimony whereof I affix my signature in presence of two witnesses.

JOHN REICHERT.
